CLAIM

The ornamental design for a carabiner, as shown and described.

DESCRIPTION

FIG. 1 is a top plan view of a carabiner, the bottom plan view being a mirror image of the top plan view.

FIG. 2 is a right view of the carabiner shown in FIG. 1.

FIG. 3 is a left view of the carabiner shown in FIG. 1.

FIG. 4 is a front view of the carabiner shown in FIG. 1.

FIG. 5 is a back view of the carabiner shown in FIG. 1; and, FIG. 6 is a perspective view of the carabiner shown in FIG. 1.

The broken lines in the drawings depict features of the carabiner that form no part of the claimed design.
